This cross-sectional view illustrates a cylinder assembly. Key components labeled include:

- K**: A bracket or support structure on the left side.
- 60**: A part positioned above the cylinder body.
- N**: A top cap or cover.
- 72**: A component located above the cylinder body.
- 61**: A part located on the right side of the cylinder body.
- 13**: A label on the right side.
- K**: A bracket or support structure on the right side.
- 11**: A label on the left side.
- 11**: A label on the right side.
- P**: A label near the bottom left.
- R**: A label near the bottom center.
- 61**: A label near the bottom right.
- 73**: A label at the bottom left.
- 73**: A label at the bottom right.

DRAFT RIGGING

John H. Link, Merion, Pa., assignor to W. H. Miner, Inc., Chicago, Ill., a corporation of Delaware

Application April 27, 1932, Serial No. 607,715

9 Claims. (Cl. 213—9)

This invention relates to improvements in draft riggings especially adapted for use in connection with mine cars.

One object of the invention is to provide a simple and efficient means for absorbing draft and buffing shocks to which mine cars are subjected in service, comprising relatively few parts, thereby economizing in cost of materials and labor.

10 A further object of the invention is to provide means of the character indicated in the preceding paragraph, wherein the construction and design are greatly simplified by providing a shock absorbing spring means of the laminated 15 spring plate type with the spring plates arranged in a group disposed transversely of the end of the car and cooperating with a single buffering head by which said group is flexed inwardly in buff, and also cooperating with yoke acting 20 means by which said group is flexed in a reverse direction in draft.

A still further object of the invention is to provide a combined buffering and draft means, which may be attached as a unit to the end of a 25 mine car of usual design without making any substantial alteration or change in the construction of the car, requiring only the substitution of the unit for the ordinary buffering head and drawbar employed on such a car.

30 Other objects of the invention will more clearly appear from the description and claims herein-after following.

In the drawings, forming a part of this specification, Figure 1 is a horizontal sectional view 35 through the end wall of a mine car, showing adjacent parts of the car structure in plan and illustrating my improvements in connection therewith. Figure 2 is a horizontal sectional view, similar to Figure 1, corresponding substantially to the line 2—2 of Figure 4. Figure 3 is an end elevational view, partly broken away, of the structure shown in Figure 1, looking from the left in said figure. Figures 4 and 5 are longitudinal, vertical sectional views, corresponding 40 respectively to the lines 4—4 and 5—5 of Figure 1. Figure 6 is a view, similar to Figure 2, illustrating another embodiment of the invention. Figure 7 is a longitudinal, vertical sectional view, corresponding substantially to the line 7—7 of Figure 1. Figure 8 is a view, similar to Figure 2, showing still another embodiment of the invention. Figure 9 is an end elevational view looking from the left in Figure 8. Figure 10 is a longitudinal, vertical sectional view, corresponding 55 substantially to the line 10—10 of Figure 8. And

Figure 11 is a longitudinal, vertical sectional view, through the end portion of a car, showing in elevation the combined draft and buffering mechanism illustrated in Figure 8.

In said drawings, 10 designates one end portion of a mine car having the usual floor 11, end sill 12, and vertical end wall 13. The end sill 12, as shown, is in the form of an angle bar having horizontal and vertical flanges 14 and 15.

Referring first to the embodiment of the invention illustrated in Figures 1 to 5 inclusive, my improvements comprise broadly a housing A; a buffering head B; a yoke member C; and a laminated plate spring D.

The housing A comprises two parts 16—16 15 fixed to the end wall 13 of the car. Each part 16 of the housing comprises spaced, horizontally disposed top and bottom walls 17—17, a vertical back wall 18, and a vertical side wall 19. The housing sections are secured in position on the 20 end wall 13 of the car by means of rivets 20—20 extending through the back walls of said housing portions 16—16 and the end wall 13 and the end sill 12 of the car. The top and bottom walls 17—17 of the two parts of the housing extend outwardly beyond the side walls 19—19, as clearly shown in Figures 1 and 2. The extended portions of the top and bottom walls are provided with vertically aligned openings 21—21 and 21—21 for a purpose hereinafter pointed out.

The buffering head B is in the form of a solid block or casting having a curved front buffering face 22 and a flat rear abutment face 23. As shown in Figures 1, 2, and 3, the block B is of such a size as to freely telescope within the two-part housing A. The head is provided with inwardly extending slots 24—24 at opposite sides thereof, which are aligned with the vertical openings 21—21 and 21—21 of the top and bottom walls 17—17 and 17—17 of the two parts of the 40 housing. Bolts 25—25 extend through the aligned pairs of openings 21—21 and the corresponding slot 24 at each side of the mechanism and serve to connect the buffering head B to the housing A so that the buffering head has a limited 45 amount of movement inwardly of the housing and is normally held against outward movement. Centrally the buffering head is provided with an inwardly extending coupling pin receiving slot 26, which serves to guide a coupling pin hereinafter 50 described.

The yoke C is arranged between the two parts 16—16 of the housing and has spaced, horizontally disposed top and bottom arms 27—27 connected at their inner ends by a vertical section 55

28. At the inner end, the yoke member C normally bears directly on the end wall 13 of the car, thereby having its inward movement limited. The top arm 27 of the yoke is provided with an outstanding lug member 29 having a forwardly projecting finger or flange 30 parallel to the arm 27 and spaced therefrom so as to accommodate a coupling link 31 therebetween. The flange 30, top arm 27, and bottom arm 27 of the yoke are provided with vertically aligned coupling pin receiving openings 32—32—32 registering with the slot 26 of the buffering head B. The aligned openings 32—32—32 of the yoke C and the registering slot 26 of the buffering head receive the coupling pin 33, which serves to connect the coupling link 31 to the yoke. The pin 33 also serves to restrict outward movement of the yoke C in draft by movement of the pin being limited through engagement with the front end wall of the slot 26 of the buffering head B. As will be understood, the buffering head, being limited in its outward movement by the retaining bolts 25—25, serves as a stop for the coupling pin 33.

The laminated plate spring D, which is disposed transversely of the end of the car, is in the form of a plurality of nested rectangular spring plates 34—34—34, which are curved in the direction of their length, as clearly shown in Figures 1 and 2. The laminated plate spring D extends through the yoke C, and the opposite ends of said spring are disposed within the two sections 16—16 of the housing A. The plates forming the spring are preferably bowed inwardly, and the central portion of the group of plates forming the laminated spring bears on the end section 28 of the yoke while the opposite ends thereof bear respectively on the opposite end portions of the buffering head B.

The operation of the improved draft and buffering device, as shown in Figures 1 to 5 inclusive, is as follows: Upon inward pressure being applied to the buffering head B, the same is forced rearwardly within the housing A, thereby compressing the laminated plate spring D against the end section 28 of the yoke which is in abutment with the end wall of the car. The laminated plate spring D is thus buttressed against the end wall of the car while being flexed and buffered. Upon a pulling or draft action being applied to the connecting coupling link 31, the yoke member C is pulled outwardly away from the end of the car, thereby compressing or flexing the laminated plate spring D against the buffering head B which at this time is held stationary by the limiting bolts 25—25. Outward movement of the yoke will be limited by engagement of the coupling pin 33 with the outer end wall of the slot 26 of the buffering head B.

60 As will be evident, the improved construction shown in Figures 1 to 5 inclusive provides a simple and efficient means which may be cheaply manufactured for absorbing both the buffering and draft shocks in connection with mine cars. In the arrangement of laminated plate spring wherein the same is flexed in one direction by the buffering head and in a reverse direction by the yoke member, the spring not only serves as the cushioning means but also functions as a transverse beam for transmitting the forces in both buff and draft so that a single cushioning means will fulfill the requirements. In other words, by employing the arrangement shown and described, four main parts only are necessary to produce the complete shock absorbing means, namely, the housing, the

buffing head, the yoke, and the laminated plate spring.

Referring next to the embodiment of the invention illustrated in Figures 6 and 7, the improved construction comprises broadly a housing E; a buffering head F; a yoke member G; and a laminated plate spring H. The housing E is also made of two parts, similar to the housing A, and is fixed to the end wall 13 of the car. The buffering head F is in the form of a block telescoped within the housing and differs from the buffering head B hereinbefore described only in that the buffering head F has a horizontally disposed, centrally arranged coupling link receiving opening 50 therein. The buffering head is connected to the housing in a manner similar to that employed in Figures 1 to 5 inclusive, the head being slotted at opposite sides, as indicated at 51—51, to accommodate bolts 52—52 extending through the top and bottom walls of the two parts of the housing E.

The yoke G is slidably arranged between the two parts of the housing E and has spaced, horizontally disposed top and bottom arms 53—53 and a connecting rear end section 54. The yoke arms 53—53 embrace the buffering head F and have vertically aligned coupling pin receiving openings 55—55 adapted to accommodate the coupling pin 56. The buffering head is provided with an inwardly extending central slot 57, which registers with the openings 55—55 of the yoke arms and slidably accommodates the coupling pin 56. The slot 57 of the buffering block intersects the coupling link receiving opening 50. The coupling link, which is indicated by 58, is engaged within the opening 50 of the buffering block F so that the coupling pin will pass through the link for operatively connecting the yoke thereto.

The laminated plate spring H is substantially the same as the plate spring D hereinbefore described but is provided with a central opening 59 in alignment with the link receiving opening 50 of the buffering head F so as to accommodate the inner end of the link 58 upon inward displacement of the same and the buffering head F.

The operation of the improved mechanism shown in Figures 6 and 7 is substantially the same as that of the mechanism shown in Figures 1 to 5 inclusive.

Referring next to the embodiment of the invention illustrated in Figures 8 to 11 inclusive, my improvements comprise broadly a housing K; a buffering head M; a yoke member N; a pair of buffering springs P—P; and a draft spring R.

The housing K comprises two parts 60—60 fixed to the end wall 13 of the car. Each housing part 60 has spaced top and bottom walls 61—61, a vertical back wall 62, and a relatively short vertical side wall 63. As clearly shown in Figures 8 and 11, the top and bottom walls extend forwardly a considerable distance beyond the side wall 63 and are provided with vertically aligned bolt receiving openings 64—64.

The buffering head M is in the form of a casting having a curved outer buffering face 65. At the inner side, the buffering head is provided with a pair of spring seats 66—66 for a purpose hereinafter pointed out. At the center, the buffering head is provided with an inwardly extending slot 67 adapted to accommodate the coupling pin 68 for sliding movement. A pair of bolts 73—73 extending through the top and bottom walls of the two parts 60—60 of the housing and through slots 74—74 provided at opposite sides of the

buffing head M connect the head to the housing and serve to limit outward movement of the buffing head and hold the same stationary in draft.

5 The yoke N is slidably disposed between the two parts 60-60 of the housing K, and comprises spaced top and bottom arms 69-69 connected by a vertical rear end section 70. The top arm 69 is provided with an outstanding lug 71 having a horizontal section or flange similar to the lug 29 of the yoke C hereinbefore described. The coupling link, which is indicated by 72, is accommodated between the upper arm 69 and the flange 71 of the lug and is connected 10 to the yoke by means of the coupling pin 68, which extends through vertically aligned openings in the lug 71 and the arms 69-69 of the yoke and works in the slot 67 of the buffing block M.

20 The buffing springs P-P are arranged at opposite sides of the mechanism and are disposed respectively in the parts 60-60 of the housing K. Each spring P has the outer end thereof engaged in the corresponding spring seat 66 of the buffing head M and the inner end bearing on the back wall 62 of the corresponding housing part.

The draft spring R is disposed within the yoke N and has its opposite ends bearing respectively on the inner side of the buffing head M and the 30 end section 70 of the yoke member.

In the operation of the improved construction as shown in Figures 8 to 11 inclusive, upon a buffing force being applied to the buffing head M, the same is moved inwardly to compress the buffing springs P-P and the draft spring R. Inward movement of the buffing head is limited by engagement of the inner end of said head with the front edges of the side walls 63-63 of the two parts of the housing. Upon a pulling 40 or draft action being applied to the yoke N, the same will be drawn outwardly, thereby compressing the draft spring R against the inner side of the buffing head M, which at such times is held against outward movement by the bolts 73-73.

45 From the preceding description taken in connection with the drawings, it will be evident that I have provided a combined buffing and draft device for mine cars, which may be applied to the end of a car to form a complete unit, thereby adapting the device for use in connection with either new cars or cars which are in service. In applying the combined unit to cars in service, it is merely necessary to remove the usual bumpers and coupling means from the end of the car and 55 attach the improved unit.

I have herein shown and described what I now consider the preferred manner of carrying out my invention, but the same is merely illustrative and I contemplate all changes and modifications 60 that come within the scope of the claims appended hereto.

I claim:

1. In a draft rigging for cars, the combination with a two-part housing fixed to the end of the car; of a transversely disposed laminated plate spring having its opposite ends seated in said parts of the housing respectively; a buffing head telescoped within said housing and engaging the opposite ends of the spring to flex the same inwardly in buff; a yoke member movable outwardly in draft, said yoke member being interposed between the two parts of the housing and embracing the laminated plate spring between the ends thereof; and abutment means on the car limiting inward movement of the yoke.

2. In a draft rigging for cars, the combination with an inwardly movable buffing head; of supporting means within which the buffing head is guided; means for limiting outward movement of said head; a yoke movable outwardly in draft, 5 said yoke being slidably supported on the buffing head and having top and bottom arms straddling said buffing head, said top arm having a connecting lug including a flange parallel to and spaced from said top arm, said arm and flange 10 accommodating a coupling link therebetween; a coupling pin extending through said flange of the lug, the top and bottom arms of the yoke, and the buffing head for connecting the coupling link to the yoke and also limiting outward movement of the yoke with respect to the buffing head; and spring means yieldingly opposing inward movement of the buffing head and outward movement of the yoke.

3. In a draft rigging for cars, the combination 20 with an inwardly movable buffing head at the end of the car; of means for limiting outward movement of the buffing head; a yoke slidably supported on the buffing head and movable outwardly in draft, said yoke having top and bottom arms embracing the buffing head; coupling means on the yoke; and spring means yieldingly opposing inward movement of the buffing head and outward movement of the yoke.

4. In a draft rigging for cars, the combination 30 with an inwardly movable buffing head at the end of the car, said head having a horizontally disposed coupling link receiving slot therein; of an outwardly movable yoke having top and bottom arms embracing said buffing head and slid- 35 ingly supporting the yoke on the buffing head; a coupling pin extending through said top and bottom arms of the yoke and the buffing head, said pin extending across the slot of the buffing head and being engageable through the coupling 40 link, said pin being movable in said buffing head to a limited extent in a direction lengthwise of the car; and spring means yieldingly opposing outward movement of the yoke and inward movement of the head.

5. In a draft rigging for cars, the combination with an inwardly movable buffing head at the end of the car, said head having a horizontally disposed coupling link receiving opening therethrough and a vertical pin receiving 50 slot communicating with said opening; of means for limiting outward movement of said buffing head; an outwardly movable yoke having top and bottom arms and a connecting vertical rear end section; a coupling pin for connecting the 55 yoke to the coupling link, said pin extending through the top and bottom arms of the yoke and the pin receiving slot of the buffing head; and a transversely disposed laminated plate spring extending through the yoke and inter- 60 posed between the buffing head and the vertical end section of the yoke, said laminated plate spring having a pocket in alignment with the coupling link receiving opening of the buffing head.

6. In a draft rigging for cars, the combination with a yoke at the end of the car, said yoke being movable outwardly in draft and having its inward movement limited by engagement with the corresponding end of the car; of housing 70 members secured to the corresponding end of the car at opposite sides of the yoke, each of said housing members having spaced top and bottom walls, a vertical outer end wall, and a vertical rear wall; means for securing said rear 75

walls of said housing members to the end wall of the car; a buffering head telescoped within said housing members; means extending through the buffering head and the top and bottom walls of each housing member for connecting buffering head to said housing members and limiting outward movement of the buffering head; and a transversely disposed laminated plate spring extending through said yoke and into said housing members and having its opposite ends bearing on the inner side of the buffering head.

7. In a draft rigging for cars, the combination with a yoke at the end of the car, said yoke being movable outwardly in draft and having its inward movement limited by engagement with the corresponding end of the car; of a buffering head movable inwardly of the car; means for limiting outward movement of the buffering head; spring means interposed between the buffering head and yoke yieldingly opposing relative movement of the head and yoke; and additional spring means opposing inward movement of the buffering head, said additional spring means being disposed at opposite sides of said first named spring means.

8. In a draft rigging for cars, the combination with a yoke at the end of the car, said yoke being movable outwardly in draft and having its inward movement limited by engagement with the corresponding end of the car; of a buffering head movable inwardly of the car; means for limiting outward movement of the buffering head; a spring within the yoke bearing on the inner side of the buffering head and yieldingly

opposing outward movement of the yoke with respect to said buffering head and inward movement of the buffering head with respect to the yoke; and springs at opposite sides of said yoke, each buttressed against the end of the car and bearing on the inner side of the buffering head and yieldingly opposing inward movement of the buffering head.

9. In a draft rigging for cars, the combination with a support secured to the end of the car, said support having a horizontal bottom wall; of a buffer head slidably supported on said bottom wall for movement toward and away from said end of the car; fixed stops on said support at opposite sides thereof, said stops having shouldered engagement with said buffer head to limit outward movement of the head; a one-piece, integral draft member movable with respect to said buffer head, said draft member including a vertically disposed follower section and means above said follower section for receiving a coupling link to connect the draft member to another car, said follower section being in horizontal alignment with the buffer head, said means for receiving the coupling link including a pair of horizontally disposed, vertically spaced arms adapted to receive a coupling link therebetween, said arms having aligned coupler pin receiving openings forwardly of said follower section; and spring means having its front and rear ends bearing respectively on the inner side of said buffer head and the forward side of said follower section.

JOHN H. LINK.
